UNITED STATES PATENT OFFICE

JOZEF PIETRZYKOWSKI, OF WARSAW, POLAND

BOAT

Application filed April 4, 1929, Serial No. 352,545, and in Poland September 8, 1928.

The object of the present invention is to provide a boat, distinguished among the boats now in use by being water-tight and closed all around, so as to prevent sinking. The improved construction makes the boat sufficiently resistible to water and steady. The boat is illustrated in the appended drawings in which:

Figure 1 shows the longitudinal sectional view of the boat on line I—I Figure 2;

Figure 2, a corresponding horizontal sectional view of the same, on line II—II, Figure 1;

Figures 3 and 4 show two different cross-sections of the hull, taken along lines V—V and VI—VI of Figure 1, respectively; and

Figure 5 shows a fragmentary section of a wooden rib.

The boat is divided into several compartments of which the front compartment 1 contains one or more cabins; the next compartment 2 is destined for the pilot, and the rear compartment 3 contains a privy 42 closed tightly from beneath by means of a cover or flap. The compartments communicate with each other by water-tight doors 4.

In the above-mentioned compartments there are provided air inlet pipes 5 and 6 adapted to be closed from the inside by valves 7 and 8. The pipes 5 and valves 7 are normally used, the pipes 6 and valves 8 being used only in case of the boat being overturned and the part of the hull shown in the drawings as the upper part thereof becoming the lower one. Air is admitted through the pipes 5 and 6 only during the heavier storms, while during fine weather the upper openings 9 are to be opened. In the walls of the hull there is provided a number of windows 41 and also a light reflector 31.

The boat is elliptical in cross-section. The main outer walls of the hull consist of wooden boards 13 extending longitudinally in respect of the boat. These boards are glued together and laid one upon another so as to make two layers. The hull of the boat is stiffened from the inside by a number of internal frames or ribs 16, held together by means of bolts or the like 18. On the outer walls are provided iron rings 19 placed around the

body of the boat. The ribs 16 are each made of a layer of wooden boards bent while treated with steam and glued together afterwards. In the front and rear parts of the hull there are provided inner stiffening ribs 21 and 22 constructed similarly to the ribs 16 and fixed to the main outer walls by bolts or the like 18. On the outside the front part of the hull is protected by an iron head 23. The stern outer wall of the hull has an iron head 39 secured to the transversal frames 22 and to the main outer walls 13.

The hull is divided by transversal partitions 4 into at least three compartments 1, 2 and 3. In the rear compartment is located a shaft for a screw propeller 25. In the same rear compartment is placed a privy closed tightly from beneath by means of a cover or flap 42. In the part 2 of the hull is located the pilot's cabin closed all around by means of side walls 27 and a floor 28. There are provided water-tight doors 45 enabling communication between the compartments of the boat. In the upper part of the pilot's cabin is placed a window 30 which is closed during bad weather and opened during good weather. Before the pilot's cabin are located reflectors 31. In the pilot's cabin is placed the steering mechanism while the motor 32 is located under the pilot's cabin. In the front part of the boat there is provided a tube 34 mounted water-tight in the body of the hull. The tube is open at its lower end, said opening being closed by a flap. Inside the tube there is located a mast 35. During heavy storms the mast is sunk into the water and prevents the overturning of the boat. On the upper deck of the hull may be placed on the outside motors 36 with air-propellers which permit to increase the speed of the boat and may be used during good weather. If these outside motors were used the mast is taken out from the above-mentioned tube and laid along the deck of the boat. The boat may thus also be used as a sailing vessel.

Referring to Figures 3 and 4 the pipes 37 extending along the whole length of the hull constitute floats which ensure steady running of the boat.

What I claim is:—

1. A boat, comprising a hull made of a plurality of layers of wood glued together and completely closed in a water-tight manner, stiffening ribs consisting of layers of wood glued to the said layers on the inside of the hull, and iron rings surrounding the exterior of the hull.
- 10 2. A boat, comprising a hull made of a plurality of layers of wood glued together and completely closed in a water-tight manner, stiffening ribs each consisting of a plurality of layers of wood, bent while treated with steam and glued together, and iron rings surrounding the exterior of the hull.
- 15 3. A boat, comprising a hull made of a plurality of layers of wood glued together and completely closed in a water-tight manner, iron rings surrounding the exterior of the hull, and forged headers covering the front and rear ends of the boat.

In testimony whereof I have signed my name to this specification.

JOZEF PIETRZYKOWSKI.
